APPARATUS FOR TIMING MECHANICAL
FUSES OF PROJECTILES

André Varaud, Geneva, Switzerland

Application May 24, 1933, Serial No. 672,701
In Switzerland June 5, 1932

6 Claims. (Cl. 86—23.1)

The invention relates to improvements in apparatus for timing projectiles provided with clockwork operated fuses of the kind comprising a member for rotating the key of a projectile 5 mechanically connected to a manually operated rotary driving member, the angular displacement of which is limited by a fixed abutment and by a movable stop carried by a graduated dial adapted to be rotated by hand independently of the driving member and to be immobilized in any angular position, the winding of the power spring of the clockwork and the regulation of the time of ignition of the projectile being effected simultaneously by the rotation of said key.

15 An object of the invention is to enable mechanical fuses with clockwork action to be automatically timed with great speed.

Another object of the invention is to provide a machine capable of automatically setting the 20 timing of any projectile that is introduced into it or that is already there at the instant a firing signal is given.

A further object of the invention is to provide a machine of the kind in question which automatically gives a signal to indicate to the gunner that the setting of the timing has been completed.

A still further object of the invention is to provide a machine of the kind in question which 30 will automatically re-set the parts to initial position as soon as the time setting is completed.

My invention consists in an apparatus for timing mechanical fuses of projectiles characterized by electro-mechanically operated means for effecting the fixing of the projectile in the holder provided therefor in the apparatus, the coupling of the driving member thereof with the movable and adjustable part of the fuse, the driving of the mechanism in the direction for timing and 40 the replacement of said mechanism to zero and by means causing these operations to occur automatically in a determined order corresponding to the timing to be effected.

The drawing illustrates an example of construction of the apparatus.

Fig. 1 is a plan view of the apparatus partly in horizontal section and in which the electric circuits are diagrammatically indicated.

Fig. 2 is a detail diagram of the electric drive.

50 The apparatus represented is composed of a box 1, inside which are the usual members of a timing apparatus, namely:—

A toothed wheel 2 carrying a mobile abutment not illustrated which by the hand wheel 3, 55 through the intermediary of a worm gear 4, can

be brought into the timing position corresponding to the indications of an indicator 5.

A toothed wheel 6 carrying an abutment, also not illustrated, which is intended to move between a fixed abutment not illustrated and the abutment of the wheel 2, the angle through which it moves determining the number of revolutions which it, through the agency of a toothed wheel 7, causes a shaft 8 to act on the winding means of the clockwork of the fuse the position of which together with that of the projectile is represented at 9 in broken lines.

Contrary to the known apparatus, the driving of the toothed wheel 6 is effected by means of an electric motor 10 and of a driving chain 11 connecting said motor to said toothed wheel by means of corresponding toothed pinions. In order to give flexibility to this drive, shock absorbing springs, such as 12, are inserted between the central shaft moved by the chain 11 and the toothed wheel 6, such a coupling being sufficiently known not to need describing in detail.

The projectile 9 can be introduced into the apparatus into a socket provided for that purpose, while the projectile can be pressed therein by an eccentric 13 and the end 14 of the fuse is gripped by any driving member 15 also not forming part of the invention.

The eccentric 13 and the driving member 15 intended to couple the shaft 8 to the end 14 of the fuse are connected together by a set of levers 16, 17, 18 so provided that by acting on the lever 18 so as to rotate it anticlockwise one simultaneously applies the driving member 15 against the end 14 of the fuse and the eccentric 13 against the body of the projectile, the movement of the lever 18 in the direction indicated being effected, by means of a plunger 19 adapted to be attracted by a coil 20. As represented, the eccentric 13, the driving member 15, the levers 16, 17, 18 and the plunger 19 are in the timing position, that is to say in the position in which the projectile is immobilized in the apparatus and the end 14 of the fuse gripped and drawn by the member 15. In this position the coil 20 is electrified, a spring 21 drawing the plunger core 19 therefrom as soon as it ceases to be electrified, thus releasing the body of the projectile and the end of the fuse.

The motor 10 possesses three terminals, one, 105 22, for the arrival of the current which a conductor conveys at 23 from the post of control, two others, 24, 25 for the departure of the current, one of them, 24 corresponding to a direction of working of the motor, which I will call the direc- 110

tion of replacement at zero, and the other, 25, to the opposite direction, which I will call the timing direction. These two terminals 24, 25 can be connected by means of two conductors 26 and 27 and an abutment 28 of the plunger core to the mass of the apparatus, which, as indicated at 29, constitutes a return to earth.

But a current issued from the post of direction through the intermediary of the arrival terminal 23 not only penetrates into the motor and according to the position of the plunger core into either of the conductors 26, 27 but further into a circuit derived from this first circuit and passing through a conductor 30, a contact 31 which will be referred to further on, a conductor 32, a firing-signal 33, a conductor 34, the coil 20 and a conductor 35 allowing of a return to earth through the intermediary of the body of the projectile, when such a projectile is in its place in the timing apparatus.

The contact 31, very slightly indicated in Fig. 1 in order not to overcrowd the drawing, is shown more in detail in Fig. 2. In this figure is found the endless screw 4 and the toothed wheel 2 which it actuates with its movable abutment 36, the toothed wheel 6 actuated by the motor and carrying an abutment 37 intended to move between the fixed abutment 38 of the frame, which serves it as zero, and the movable abutment 36 of the wheel 2, which determines the displacement thereof necessary to a given timing. The abutment 37 further comprises a finger 39 of an armature, which is connected by means of a ring 40 and of a corresponding brush, to the conductor 32 for example, connecting it to the signal 33, whereas the other armature 41 is connected by a ring 42 and a corresponding brush to the conductor 30. The armature, to which the finger 39 is secured, is formed of a spring 43. It is easily seen that by displacing the wheel 6 and the members carried by it in the clockwise direction with regard to Fig. 2, the finger 39 will at a given moment encounter the abutment 36, thus immobilizing the armature 43, the flexibility of which will still allow the wheel 6 to continue its course by separating the armature 41 from the armature 43, that is to say by breaking the circuit of the conductors 30, 32. If rotated in the contrary direction, the wheel 6 will only be stopped by the encounter of its abutment 37 with the fixed abutment 38 of the frame and, during the whole passage between the abutment 38 and the abutment 36, the members constituting the abutment and the contacts of the wheel 6 will keep the circuit 30, 32 closed.

The operation of the apparatus just described is as follows:—

The apparatus being at rest, that is to say no projectile being introduced therein and the abutments 37 and 38 touching each other, the members are said to be at zero. If, at this moment, the indicator 5 actuated from the post of direction indicates a timing value through the displacement of an index giving a measurement of the displacement which the abutment 36 of the wheel 2 is to be made to perform, it suffices for the gunner of the apparatus to displace the abutment to the extent indicated, by actuating to this effect the hand wheel 3. In doing so, he keeps the timing apparatus constantly regulated, in correspondence with the momentary timing value which is transmitted to him.

At the moment that the timing is to be effected, which moment corresponds, in a quick firing, to the moment of the signal to fire, a

current is sent into the apparatus by means of the terminal 23 and into the two following circuits:—

(a) Circuit including the terminal 23, the terminal 22, the conductor 30, the contacts 31, the conductor 32, the fire signal 33, the conductor 34, the coil 20, the conductor 35 and the earth, under the condition that there is a projectile in the apparatus. If there is no projectile in the apparatus this circuit then is open.

(b) Circuit including the terminal 23, the terminal 22, the motor 10, the terminal 24, the conductor 26, the abutment 28 of the plunger core 29 and the earth, said circuit corresponding to the direction of action of the motor, called return to zero, the purpose of which direction being to apply the abutment 37 of the wheel 6 against the fixed abutment 38 of the frame, that is to say, to ensure the start to zero the moment the direction is reversed.

The firing signal being maintained, if a projectile is introduced into the apparatus, it results in a closing of the circuit previously styled a, and this through the contact at the mass created by the projectile by means of the conductor 35. The signal lights up, the coil 20 is electrified and the plunger core 19 is attracted into the position represented. The projectile is immediately locked by the eccentric 13 and gripped by the driving member of timing 15. But at the same time, the abutment 28 of the plunger core 19 breaks the motor circuit passing through the conductor 26, in order to close a fresh motor circuit of reversed working through the conductor 27. The motor starts to rotate in the direction of the timing, that is to say in the direction in which the abutment 37 of the toothed wheel 6 quits the fixed abutment 38 of the frame and actuates the shaft 8 and the driving member 15 in the direction where the fuse is timed. This movement continues until the instant that the finger 39 touching the mobile abutment 36, the armatures 41, 43 are separated from each other, which amounts to saying that the contacts 31 of Fig. 1 open the circuit feeding the coil 20. This circuit being opened, the plunger core 19 ceases to be attracted and the spring 21 restores it to its starting position where its abutment 28 breaking its contact with the conductor 27 re-establishes the earthing of the conductor 26, at the same time that the projectile is released and can be extracted, the fire signal being extinguished to indicate that the timing is terminated.

At this moment the projectile is withdrawn, whilst the motor 10, whose circuit passing through the terminal 24 and conductor 26 is closed, begins to rotate in the direction contrary to the direction of the timing and returns the wheel 6 to zero.

The return to zero of the wheel 6 produces the closing of the contact 31 and if the signal given by the post of direction persists, that is to say if the firing is to continue, it suffices to introduce a fresh projectile into the apparatus in order that the operations just described may begin again.

If at the moment when the firing signal is given, a projectile is already in its place in the apparatus, the operations described are immediately disengaged, as the circuit passing through the conductor 35 and the projectile is closed from the moment that the firing signal is started.

As can be understood the apparatus described enables the mechanical fuses with clockwork action to be timed with great speed and its working

is automatic, seeing that it times any projectile that is introduced into it or that is already there at the moment when the firing signal is given, and that this signal is automatically extinguished 5 in order to show the gunner that the projectile is timed when this operation is terminated. Finally the apparatus returns to zero as soon as the timing is terminated.

One will therefore preferably employ the apparatus while constantly leaving therein a projectile in timing position, so that the order given from the post of direction may be immediately perceived through the illuminating of the signal, the timing being then effected without loss 10 of time. It is clear, on the other hand, that the gunner having at his disposal after timing for extracting the projectile only the time taken by the members of the apparatus to stop and change their direction so that he must proceed 15 with this operation without delay at the instant that the firing signal is extinguished.

It must be added that the motor 10 should be of a type, capable of maintaining the wheel 6 at zero, and of remaining under tension whilst still 20 being immovable, said motor however does not have to perform a large number of revolutions on itself, but at the most only one or two revolutions, so that it should be constructed as a servo-motor capable of instantaneously furnishing 25 a relatively powerful couple. The action of such a servo-motor is therefore as it were instantaneous, that is to say that either the timing, or the return to zero, is effected in a fraction 30 of a second separated by the short instant arising from the inertia of the masses in action.

What I claim as my invention and desire to secure by Letters Patent of the United States is:—

1. Apparatus for timing mechanical fuses of projectiles, comprising a projectile holder, means for locking the projectile in operative position in said holder, a driving member adapted to be coupled with the fuse to set the timing thereof, means including an electromagnet for actuating 40 the locking means and the coupling of the driving member with the fuse, an electric motor adapted to drive said member, means controlling the amount of drive of said member, and an electrical system in which said electromagnet and 45 motor are connected and including movable contacts operated by the electromagnet and the motor for determining actuation of the locking means, coupling of the driving member, driving of the same in the timing direction, and restoration 50 of the same in the timing direction, and restoration

of the apparatus to initial condition, in proper sequence.

2. Apparatus according to claim 1, in which the electromagnet has an armature mechanically connected to the projectile locking means and the drive member, and including a spring tending to hold said armature in projectile releasing position and to retract the drive member from the fuse. 80

3. Apparatus according to claim 1, in which the electromagnet has its energizing coil arranged in a circuit of the electrical system containing a contact which is closed by inserting a projectile in the holder and also containing a movable contact which is opened by the electric motor when the timing of the fuse is completed. 85

4. Apparatus for timing mechanical fuses of projectiles, comprising a projectile holder, means for locking the projectile in operative position in said holder, a driving member adapted to be coupled with the fuse to set the timing thereof, means including an electromagnet for actuating the locking means and the coupling of the driving member with the fuse, an electric motor adapted to drive said member, means controlling the amount of drive of said member, an electrical system in which the energizing coil of the electromagnet and the motor are connected, said system including movable contacts operated by the electromagnet and a movable contact which is opened 90 by the electric motor when the timing of the fuse is completed. 95

5. Apparatus according to claim 1, in which the electromagnet and a movable contact which is opened by the electric motor when the timing of the fuse is completed, and a signal device in series with said last-mentioned contact, said contacts determining actuation of the locking means, coupling of the driving member, driving of the same in the timing direction, signaling the completion of timing, and restoration of the apparatus to initial condition, in the proper sequence. 100

6. Apparatus according to claim 1, in which the electric motor is rotatable in two directions to effect the time setting and the restoration, respectively. 105

7. Apparatus according to claim 1, in which the electromagnet carries a movable contact on its armature adapted in one position to close a circuit of the electrical system for driving the motor in time-setting direction when the operations of locking the projectile in the holder and the coupling of the driving member to be fused are terminated, and in another position to reverse the direction of rotation of the motor when the projectile has been released and the driving member disengaged from the fuse. 110
